UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CARRYING MECHANISM FOR CALCULATING-MACHINES.

1,272,083.

Specification of Letters Patent.

Patented July 9, 1918.

Application filed August 27, 1915. Serial No. 47,644.

To all whom it may concern:

Be it known that I, EDGAR E. PHINNEY, a citizen of the United States, resident of New York, in the county of New York and State of New York, have made a certain new and useful Invention in Carrying Mechanism for Calculating-Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a sectional view of a calculating machine showing the invention applied thereto.

Fig. 2 is a detail side view of one of the reciprocating pawls or teeth, as applied, with the plunger depressed and the pawl moved into engagement with the intermediate gear.

Fig. 3 is a similar view with the plunger and pawl in normal position.

Fig. 4 is a detail side view of one of the pawls or teeth.

The invention has relation to carrying mechanism for calculating machines of the type shown in my co-pending application for letters Patent, Serial Number 41,343, and in the reissue patents to Baldwin, dated December 8, 1914, No. 13,841 and No. 13,842, and particularly to the pawls or teeth of such carrying mechanism, the object being mainly to provide carrying pawls or teeth that will move in a straight path, and to simplify the manufacture and assemblage.

The invention consists in the novel construction and combinations of parts, as hereinafter set forth.

In the accompanying drawings, illustrating the invention, the numeral 73 designates the shaft of the carrying mechanism, having thereon a plurality of collars provided each with two radial arms *m*, *m*, fast thereto, each radial arm being provided with a carrying pawl or tooth *j*. All of these collars are fixed upon the shaft, and the carrying pawls are arranged in two oppositely pitched spiral lines, each series or set of pawls extending about one-fourth around the shaft, both together about one-half around, and the two series nearly intersect-

ing, or ending adjacent to each other. The carrying mechanism of the patents to Baldwin referred to may, of course, be used with substitution of the special pawl devices of this application, instead of the carrying mechanism of the co-pending application, herein described.

4 designates the shaft of the primary or selecting wheels, 5 the selecting wheels thereupon, 13 the registering wheels, 12 the intermediate gears and *p*, the reciprocating plungers, working in slots of collars and in clearance holes of the shaft of the intermediate gears, and having lower cam heads *s*, and upper beveled ends, engaged by the lateral studs *q*, of the registering wheels, to depress the plungers so that their heads will, in the rotation of the carrying mechanism, be in position to engage and throw the pawls or teeth of said mechanism.

These pawls, in the present case, slide laterally, to one side or the other, in straight paths in directions parallel to the shaft 73, in guideways of the radial arms *m*, the pawls being usually of rectangular form, provided with open-end notches or recesses *o*, at each end, forming upper and lower straight end arms *r*, *r*', parallel to said shaft, the upper arms sliding in guideways *n*, and the lower arms sliding in guideways or perforations *t*, of the opposite members of the radial arms. The guideways *n* and *t* have straight walls parallel to the said shaft. The pawls are returned to normal position by suitable springs, as coiled springs *u*, after operation by the cam heads of the plungers. The plungers are returned to normal position by radial arms 14, fast upon the shaft of the carrying mechanism and located midway between the two series of carrying members.

The operation of the pawls is the same as that of the pawls described in the patent hereinbefore referred to, but, as the shortest path is taken by the pawls from one wheel to the next, lost movement is eliminated and time is saved. The pawls are also enabled to be made in simpler pattern, with fewer parts, and time is saved in assembling.

What I claim is:

In a calculating machine, carrying mechanism including independently movable gears, a reciprocating plunger for each

gear, a rotary shaft, members upon said shaft having guideways provided with straight portions parallel to said shaft, reciprocating teeth having straight portions 5 parallel to said shaft and slideable in straight paths in said guideways against the straight portions thereof, and means for depressing the plungers individually once during each rotation of the corresponding 10 gears, each of said teeth being engaged by

the corresponding plunger in the rotation of said shaft and thrown in the shortest path into engagement with the succeeding gear.

In testimony whereof I affix my signature 15 in presence of two witnesses.

EDGAR E. PHINNEY.
